UNITED STATES PATENT OFFICE.

ROBERT MCNIE, OF NEW YORK, N. Y.

LITHOGRAPHIC PRESS.

Specification of Letters Patent No. 31,818, dated March 26, 1861.

To all whom it may concern:

Be it known that I, ROBERT MCNIE, of No. 541 Hudson street, in the city, county, and State of New York, have invented a new and Improved Lithographic Press; and I do hereby declare that the following is a full, clear, and exact description of the same, reference being had to the annexed drawings, making a part of this specification, in 10 which—

Figure 1, is a side elevation of my invention. Fig. 2, a transverse vertical section of the same, taken in the line x, x , Fig. 1. Fig. 3, a transverse vertical section of the 15 same, taken in the line y, y , Fig. 1. Fig. 4, a plan or top view of the same. Fig. 5, a longitudinal section of the same, taken in the line z, z , Fig. 4. Figs. 6, 7, 8, and 9, are views of cams employed on the machine. 20 Fig. 10, a detached view of a ratchet and arm or tappet which pertains to the invention.

Similar letters of reference indicate corresponding parts in the several figures. 25 To enable those skilled in the art to fully understand and construct my invention, I will proceed to describe it.

A, represents a framing which may be constructed in any proper way to support 30 the working parts of the machine, and B, is a reciprocating bed which is placed on the upper part of the framing A, and rests on friction rollers a, a . To the under side of the bed B, at each side there is secured a 35 rack C, into which pinions b, b , on a shaft D, gear. One of the rollers a , on which the bed B, rests is placed loosely on shaft D, and at one end of said shaft a wheel E, is secured, said wheel having an internal gear c , 40 into which a pinion d , gears.

F, is a shaft which has three pulleys e, f, g , placed loosely on it, the central one f , being an idle pulley and the other two working ones. The pulleys e, g , are operated by 45 the same belt, and the pulley e , has the pinion d , attached to it, while the pulley g , has a pinion d' , attached, the latter pinion d' gearing into a wheel d'' , on shaft D.

G, is a belt shipper which may be constructed in the usual way. This belt shipper is placed in the upper part of the framing and the upper end of a lever H, is connected to it, the lower end of lever H, being secured to a shaft I, which is placed longitudinally in the lower part of the framing A, and has an upright rod or lever J, se-

cured to it near its outer end, and has also a small arm or tappet h , secured to it, the latter being shown clearly in Fig. 4.

K, is a ratchet wheel which is placed on a transverse shaft L, in the lower part of the framing. The ratchet K, is perforated with holes i , near its periphery, said holes being at equal distances apart, and one or more of them provided with pins j , the use of which 65 will be presently shown.

L', is a pawl which engages with the ratchet K, and is attached to a lever M, which is secured to a rock-shaft N, at the lower part of the framing. To each end of 70 the rock-shaft N, there is secured an upright arm O, the upper ends of which are slotted longitudinally to receive the arms k, k , of a carriage P, which is allowed to travel freely back and forth on the framing and 75 has two ink rollers Q, Q, fitted on it.

R, is a shaft which is placed transversely in the framing A, at one end and has a crank-pulley S, placed on it to which pulley a rod T, is attached. The rod T, near its 80 front end has a semi-circular bearing l , which at certain times catches over a pin m , projecting from the lever M, see Fig. 1.

U, is a shaft which is placed transversely at the end of the framing near where the 85 ratchet K, is placed. The shaft U, has an arm V, secured to it, and from the end of said arm a pin n , projects at right angles, the pin being under the rod T.

To one end of shaft U, there is attached 90 an arm or lever W, which is connected by a link o , with a lever X, the fulcrum p , of which is at the lower part of the framing. The end of lever X, opposite to the end where the link o , is attached has an upright 95 q , attached to it, the upper end of which bears against a flanch r , on the face of a cam wheel Y, which has an internal gear s , into which a pinion Z, on the shaft D, 100 meshes, see Fig. 3. On the face of the wheel Y, there are secured two projections t, t' , one of which t , is in contact with the flanch r , the other one t' , being some distance from the flanch.

A', is a cam wheel which is placed on a 105 shaft B', the same shaft that the cam wheel Y, is secured to. The cam wheel A', has two ribs or strips u, u' , secured to its periphery circumferentially. The ribs or strips u, u' , are of equal length and do not quite extend around the wheel A'. Spaces 110 are allowed between their ends, one space

v, being open and the other one being closed by a flap *w*, the latter being shown in Fig. 4, the space *v*, being shown by dotted lines in Fig. 2.

5 On the upper part of the framing A, there is placed transversely a box or casing C', in which a scraper D', is placed, and allowed to rise and fall freely therein. In the upper part of the box or casing there 10 is a shaft *a'*, which has a toggle D'', placed loosely on it, the lower end of which bears on the scraper D', as is shown clearly in Fig. 2. The toggle D'', has an arm *b'*, attached to it, the lower end of which is connected by a link *c'*, to a lever E', which is secured to a shaft *d'*, at one side of the framing. The lower end of the lever E', is provided with a swinging pin *e'*, shown clearly in Figs. 1, 2, and 3. This pin is 15 over the face or periphery of the cam-wheel Y. On the shaft *d'*, there is also secured a pendent arm F', to the lower end of which a horizontal bar G', is connected, said bar G', being provided with a 20 shoulder *f'*, which catches against a pin *g'*, attached to the lever H, see Fig. 2.

H', is a rod which is secured at one end to a lever I', placed loosely on the shaft U. The opposite end of this rod extends 25 underneath the horizontal bar G', and the lever I', extends upward about as high as the lever J.

J', is a sliding box which is placed at the front side of the box or casing C'. The box 30 J', contains a moistened sponge and said box is allowed to rise and fall freely by the working of a bent lever K', which is connected at its outer end by a link *h'*, with the upper part of an arm L'', the lower end 40 of said arm being fitted loosely on a shaft *i'*, attached to the framing. The arm L'', has a pin *j'*, projecting from it and this pin bears against the face of the cam wheel A'.

M', is a tympan which is constructed of 45 leather or other suitable flexible material. This tympan is secured at both ends to the bed B, and it passes through a slot in the scraper D', and around suitable rollers *k'*, on the framing. The arrangement of the 50 tympan is shown clearly in Fig. 5.

To the outer end of the bed B, a horizontal arm l', is attached, said arm having a beveled plate *m'*, at its end as shown clearly in Fig. 4.

55 The operation of the press is as follows. The shaft R, is rotated continually, and at the commencement of the operation the stone shown in red outline, having upon its face the design from which the impressions 60 are taken, is placed on the bed B, the latter being moved back to its fullest extent in the direction indicated by arrow 1. As the bed B, reaches the extent of the movement indicated by the arrow 1, and the stone is properly inked the bed B, in consequence of the

pinions *b*, *b*, gearing into the racks C, C, will be moved underneath the scraper D', in the direction indicated by arrow 2, (the belt being on pulley *e*), and the impression will be given the sheet which was placed on the stone prior to the movement of the bed B, in the direction indicated by arrow 2. As the bed B, approaches the end of this latter movement, the scraper D', is thrown up from the stone by springs *a'*, *a'*, in consequence of the lower end of the lever E', being acted upon by the projection *t'*, and the toggle D'', operated so as to allow the scraper to rise under the action of the springs *a'*. At this time the box J', containing the moistened sponge is depressed in consequence of the pin *j'*, of the arm L'', being opposite the flap *w*, between the ends of the ribs or strips *u*, *u'*, the pin *j'*, being forced at the outer sides of the strips *u*, *u'*. At this time also the belt shipper G, throws the belt on the pulley *g*, and the movement of the bed B, is reversed, the bed moving in the direction indicated by arrow 1, and the stone is wiped and moistened by the sponge in box J', the printed sheet being taken off the stone by the tympan M', as the stone and bed move in the direction of arrow 1. As the bed B, approaches the termination of its movement in the direction of arrow 1, the box J', is elevated in consequence of the pin *j'*, of the arm L'', being opposite the space *v*, a spring *v'*, drawing the pin *j'*, through the space *v*, to the inner sides of the strips *u*, *u'*, and the scraper 100 D', is depressed in consequence of the projection *t*, of the wheel Y, striking the pin *e'* of lever E'. The plate *m'*, also actuates the lever J, and the lever H, throws the belt shipper which moves the belt from pulley 105 *g*, to the idle pulley *f*, and the bed B, therefore remains stationary. At this instant the upper end of the upright *q*, falls in a notch *q'*, in the flanch *r* of the wheel Y, and the pin *n*, of the arm V, which supported the rod T, and kept the bearing *l*, above the pin *m*, of lever M, is allowed to descend and fit on the pin *m*, and the lever M, will consequently be vibrated back and forth, the arms O, O, giving a reciprocating 110 movement to the carriage P, the rollers Q, Q, of which ink the stone. At every vibration of the carriage P, the pawl L', turns the ratchet K, the distance of one tooth, and when a pin *j*, strikes the small arm *h*, of shaft I, the shaft I, is turned and the belt shipper G, throws the belt from the idle pulley *f*, to the working pulley *e*, and the arm V, and rod T, are again elevated, the bearing *l*, of rod T, being elevated above 115 the pin *m*, of lever M, in consequence of the wheel Y again turning and the edge of flanch *r*, passing down the upright *q*. This movement of the arm V, stops the inking device and the bed B, again moves in the 120 125 130

direction indicated by arrow 2, a fresh sheet being laid on the tympan. The operation of printing is then repeated as previously described.

5 The ink rollers Q, Q, may be made to pass over the stone as many times as desired by having more or less pins in the ratchet K.

The bar G', may at any time be thrown up from the pin g, of the lever H, so as to 10 prevent the belt shipper G, being actuated by lever E', by actuating the lever I'.

I would remark that in lieu of the cam wheels A', Y, straight bars A'', B'', as 15 shown in Figs. 8, and 9, may be used, said bars having a reciprocating movement and provided respectively with projections t'', t'', and strips u'', u'', corresponding with those on the cam wheels. I would also remark that the projections and strips above named 20 as well as those on the cam wheels may be adjusted so as to regulate the movement of the scraper D', and box J', according to the length of the stone. I would further remark that the tympan M', may be tightened 25 at any time by adjusting one of the rollers k', the same being placed in adjustable bearings k'', see Fig. 5. I would also remark

that a water fountain with a woolen cloth or siphon may be employed to keep a constant supply of moisture in the sponge. A 30 wiping roller may also be attached to the sponge box and driven by a pulley on one end coming in contact with the belt when on pulley g.

Having thus described my invention, what 35 I claim as new and desire to secure by Letters Patent; is,

1. The arrangement of the ratchet K, pawl L', lever M, reciprocating rod T, ink carriage P, arm V, levers W, X, upright g, 40 and the notched flanch r, or its equivalent for the purpose of forming an automatic inking device as and for the purpose set forth.

2. The pendent arm F', attached to shaft 45 d', bar G', provided with shoulder f', and attached to arm F, in connection with the lever H, and belt shipper G, all being arranged as shown for automatically shipping the belt as set forth.

ROBT. McNIE.
